SMOKE TREATMENT AND CONTROL FOR
SMOKE HOUSES

Stanley L. Gershel, New Philadelphia, Ohio, assignor to Gershel Smoke Equipment Co., New Philadelphia, Ohio, a corporation of Ohio

Application May 2, 1949, Serial No. 90,922

7 Claims. (Cl. 99—259)

1

This invention relates to smoke houses.

An object of this invention is to provide a treating compartment within and through which the circulation of smoke is accurately controlled.

An additional object of this invention is to provide a closed circuit for the smoke within which the treating compartment is a part, the smoke being fed thereto along the flow path from a delivery duct, rises by a combination of natural flow and a draft promoting device, to a plurality of specially positioned and designed ventilators to an outlet duct. The circuit is completed between the outlet and inlet by the provision of a fan and a heating unit as parts thereof.

Another object of this invention is to provide and feed a fresh supply of smoke into the circuit by delivery thereof through a wall of the compartment at a point spaced from the inlet and outlet ducts.

Still another object of this invention is to provide an efficient smoke producing unit supplying the fresh smoke for the compartment, which unit not only produces the smoke but also treats the smoke before its entry into the compartment, to remove undesirable matter therefrom.

And another object of this invention is to provide a smoke circuit which reduces the fire hazard therein, particularly protecting the more costly elements of the apparatus such as the fan and heating units.

And an additional object of this invention is to provide a replacement unit for cleaning the smoke within the smoke producer which eliminates costly shut downs, permitting one unit to be in operation while the replaced unit is being reconditioned.

Other objects and advantages of this invention relating to the arrangement, operation and function of the related elements of the structure, to various details of construction, to combinations of parts and to economies of manufacture, will be apparent to those skilled in the art upon consideration of the following description and appended claims, reference being had to the accompanying drawings forming a part of this specification wherein like reference characters designate corresponding parts in the several views.

Referring to the drawings:

Fig. 1 is a diagrammatic side elevation showing an arrangement of component parts of the system including the smoke producer and a food treating chamber;

Fig. 2 is a plan view of the food treating chamber of Fig. 1;

Fig. 3 is a diagrammatic showing of a multiple food compartment system with the controls therefor;

Fig. 4 is a plan view of the smoke producer;

2

Fig. 5 is a view from the right of Fig. 4;

Fig. 6 is a side elevation of the smoke producer unit from the left of Fig. 5;

Fig. 7 is a perspective view of a replacement unit for treating the smoke within the producer;

Fig. 8 is a side elevation of the unit from the right of Fig. 5; and

Fig. 9 is an enlarged showing of a portion of Fig. 8, parts being broken away.

The system herein, for purposes of detailed description, may be divided into two major parts, the smoke producer and the food treating chamber. Interconnecting ducts, controls and heat supplies for the food treating chambers may also be considered as a third subject. For an additional object of this invention is to provide a smoke house system wherein a plurality of food treating compartments may be employed, individually controlled and operated, while all are supplied with smoke and heat from common units within the system and all interconnected with a common control.

A smoke producer 10 is provided embodying novel features which so handle and treat the smoke that a continuing supply of smoke, free from deleterious substances, is delivered to one or more food treating chambers 12 wherein the smoke is circulated and reheated in a predetermined circuit.

30 *The smoke producer*

The smoke producing unit 10 is a sheet metal hexahedral housing with fire-door side 14, opposing side 16, fan housing end 18 and opposing end or feeder drive side 20. This housing has an open top area 22 leading into fuel hopper 24 which tapers inwardly and downwardly as defined by plates 26, 28. The plate 26 extends partially across the lower region of the hopper 24 toward the lower edge of plate 28 and provides a lateral discharge opening 30 between the plates for fuel to pass from the hopper into firebox 32 formed by a suitable fire-brick lining 34.

Selected fuel, such as sawdust, chips and the like are fed into the hopper 24 through the open top 22 and are stirred by a revolving agitator 45 formed with a series of paddles 36 mounted on shaft 38 driven through chain belt 40 from speed reduction transmission unit 42, in turn driven by motor 44 mounted in recess 46 within the 50 housing.

The shaft 38 has a second belt connection 48 to shaft 50 which rotates drum 52 adjacent to and along the discharge opening 30, which drum serves as a valve feed and by means of rib or 55 flight 54 therealong intermittently discharges a quantity of fuel into the combustion chamber.

This arrangement provides the fuel feeding portion of the apparatus driven from a single source. The fuel is fed onto a fire which is controlled by draft regulator mechanism 56 limiting

the air flow into the fire bed from ducts 58 through the lining 34. A clean-out 60 is conveniently located at one end of the fire-box and a fire inspection door 62 is placed on the side 14.

Operation of the damper 56 regulates the smoke production from the fire and the smoke passes through vent 64 into the smoke treating unit 66. This vaporizing device 66 is a built-up unit fabricated from sheet metal to provide a labyrinth therethrough and may be placed into the smoke producer and removed at will for cleaning and reconditioning purposes. A like unit is inserted during the cleaning operation thereby removing the necessity of shutting down the smoke producer while the smoke treating unit is serviced for reuse. This unit fits into a chamber 68 within the producer and is sealed and locked therein by means hereinafter described in detail.

Smoke treating unit

This unit 66 receives the smoke from the vent 64 into chamber 70, through which the smoke travels downwardly escaping through open bottom 72 into chamber 74. In its downward flow, the smoke is washed by passing through spray 76 supplied by nozzle 78 fed through a pipe 80 connected by a union 82 with supply line 84. In replacing the vaporizing unit, this union 82 allows the spray supply to be readily disconnected and reassembled.

Condensation and the wash water carrying the matter removed from the smoke falls onto floor 86 of the chamber 74 which floor is inclined downwardly toward drain 88. The smoke reverses its flow direction within the chamber 74 and passes therefrom through aperture 90 into chamber 92 and continues therethrough in a substantially horizontal path to flow out of the chamber 92 through opening 94 into fan chamber 96.

The blades 98 of a fan 100 are rotated within this chamber 96 as driven by a belt 102 exterior of the unit 66, extending from motor 104 mounted in a recess 106 inwardly in the unit 10 from the side 18. Differential pulleys 108 on the fan and motor permits a variation of fan speed to determine the pull or suction of the smoke through the unit 66 and its flow rate as it is expelled through aperture 110 into duct 112 upwardly extending from the unit to the producer exterior where it is delivered to duct 114, by which it is delivered to the food treating portion of the system.

The smoke chambers 70, 74, 92, together with the fan chamber 96 are fabricated into a unit for ready replacement as it is the zone between the fire and delivery duct through which the smoke passes wherein the major deposits collect from the smoke. This includes ashes, tars and other products of combustion as well as foreign matter which might be carried from the burner.

The unit chambers are built so that each have an open side permitting easy cleaning. The unit 66 is placed in its mounting chamber 68 and the open sides of the chambers 70, 74 and 92 are draped and closed by a plate 116 mounted by bolts 118 to the housing. Gaskets may be used with the plate or other closures described herein. This plate 116 extends across the side 16 to cover the smoke chambers and is provided with extensions 120 on either side 18, 20 to provide a substantial mounting. The extension 120 on the side 18 may also engage plate 122 which not only closes the open side of the fan chamber 96 but serves as a mounting for the fan 100.

Inspection ports 124 may be located at various strategic places along the plate 116 as well as adjacent thereto, for entry into the various sections of the producer which might need attention.

The treating chambers

The smoke flowing through duct 114 may be delivered directly to a single chamber 12 or in 10 the employment of a multi-chamber system, the smoke will flow to a manifold 126 from which branch ducts 128 carry the smoke into a plurality of chambers 12.

A duct 128 preferably enters a chamber 12 adjacent the top and at one side thereof out of 15 the direct path of the smoke circuit through the chamber. This feeds a fresh supply to a closed circuit for maintaining the smoke value of the circuit.

20 The smoke circuit has its entry into the compartments by means of ports 130 in the sides of duct 132 extending lengthwise along the center of the compartment floor 134, and billows outwardly and upwardly throughout the entire compartment interior. During this movement, portions of the smoke permeate such food items as 25 may be stacked or hung within the smoke house. The natural flow of the smoke augmented by mechanical means, is withdrawn through anemostats 136 or other suitably baffled ventilators into outlet duct 138. These anemostats are arranged about the ceiling 140 of the compartment in such a manner as to control distribution suction so 30 the smoke circulates about the entire interior.

35 The outlet duct 138 extends to fan 142 driven by motor 144 and the smoke is forced by the fan from duct 138 into housing 144' and therethrough to duct 146 and thence back to duct 132. Within the housing 144' heat exchange units 148, herein 40 shown in Figs. 1 and 2 as a pair of steam heated space heaters, reheat the smoke to maintain the desired curing temperatures within the circuit.

The smoke inlet 128 which may be regulated by 45 manually operated damper 150 is delivered at a point remote from the outlets 136. While this arrangement provides ample replenishment, any possible sparks which might have escaped the smoke producer or static developed along the path will be extinguished before they reach the duct 138 thereby eliminating a fire hazard to the circulating and heating equipment. The ducts 132 and 146 are so routed they do not interfere in the loading or unloading of the compartments 50 which open at both ends.

55 The employment of a smoke producer and a plurality of curing chambers may be arranged for economical operation as for example, the lay-out illustrated in Fig. 3. Herein the outlet ducts 132 from each compartment feeds into a common duct 152 carrying the smoke from all chambers to a heating unit 154 and returned by a manifold 156 to the ducts 132. This heating unit may be gas fired, the burners controlled by a motor-driven valve 158 having connections 160 to a control panel or box 162. Lines 164 may also extend from this control to a thermo-couple 166 within each chamber 12. Lines 168 connect motor-driven dampers 170 in the ducts 128 to the panel while lines 172 connect motor-driven dampers 174 placed within the ducts 132.

60 Interconnecting mechanisms at the central panel will operate the dampers 170, 174 in response to the temperatures within the chambers as affecting the couples 166. Each chamber will 65 have its temperature individually controlled by 70

regulation of the dampers in its supply ducts and in event all chambers are cut off, the valve 158 will automatically close for conservation of gas supplied to the unit 154.

It is to be understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing from the spirit of the invention. The language used in the specification relating to the operation and function of the elements of the invention is employed for purposes of description and not of limitation, and it is not intended to limit the scope of the following claims beyond the requirements of the prior art.

What is claimed and is desired to secure by United States Letters Patent:

1. A smoke producer for smoke houses comprising a housing having a fire-box therein, a chamber in said housing open along one side of the housing, a vent for smoke from the fire-box into said chamber, a duct remote from said vent for conducting the smoke from said chamber out of the housing to its place of use, and a smoke treating unit insertible into said chamber through the open side, said unit having an inlet and an outlet to register with said vent and duct and thereby cause the smoke to travel through said unit while said unit is in the chamber.

2. The structure set forth in claim 1 wherein said unit includes a plurality of chambers therein open in a series one into another forming a labyrinth for the smoke to flow therethrough.

3. The structure set forth in claim 1 wherein said unit includes a plurality of chambers therein opening into each other in a continuous series thereby forming a labyrinth passage for the smoke therethrough, and a fan in one of said chambers providing means for propelling said smoke through the unit.

4. The structure set forth in claim 1 wherein said unit includes a plurality of chambers therein opening into each other in a continuous series thereby forming a labyrinth passage for the smoke therethrough, the first chamber receiving

the smoke from said vent having its opening thereto adjacent its upper region and provided with an open bottom and the chamber receiving the smoke therefrom positioned therebelow to receive the smoke through the open bottom thereby causing said smoke to flow through the first receiving chamber in a substantially vertically downward direction.

5. The structure set forth in claim 1 wherein said unit includes a smoke receiving chamber apertured to cause said smoke to flow downwardly therethrough, a nozzle disposed in the path of the flowing smoke, and a liquid supply to said nozzle to be sprayed therefrom across the smoke in its downward path.

10 6. The structure set forth in claim 1 wherein said unit includes a first smoke receiving chamber apertured to cause said smoke to flow downwardly therethrough, a spray device for the smoke in its downward path, a second chamber beneath said first chamber for receiving the smoke, spray and condensation products developed in the unit, and a drain for said second chamber.

15 7. A smoke producer comprising a housing, a fire-box in said housing, a recess extending inwardly from one side of said housing, a vent from said fire-box into said recess, an outlet duct from said recess, a unit insertible into said recess having openings to register with said vent and duct whereby smoke from said vent to the duct will be directed through said unit, said unit including a plurality of chambers therein opening into each other in such a manner as to form a labyrinth path for the smoke therethrough, at least one of said chambers having a side open toward the housing exterior, and a plate mountable on said housing to lock said unit in the recess and close the open side of said chamber.

STANLEY L. GERSHEL.
